UNITED STATES PATENT OFFICE.

THOMAS F. NOLAN, OF NEW YORK, N. Y.

PLATEN OR ROLLER FOR TYPE-WRITING MACHINES.

No. 854,429.

Specification of Letters Patent.

Patented May 21, 1907.

Application filed July 10, 1906. Serial No. 325,452.

To all whom it may concern:

Be it known that I, THOMAS F. NOLAN, a citizen of the United States of America, and a resident of New York, in the county and State of New York, have invented certain new and useful Improvements in Platens or Rollers for Type-Writing Machines, of which the following is a specification.

This invention has reference to improvements in a novel platen or roller for typewriting machines and the like and the method of making same.

It is the special object of this invention to provide a platen or roller for typewriting machines which is very cheaply manufactured and may be easily repaired without practically any cost.

The invention further consists in the method of lacing or stitching together a piece of felt for the purpose of forming a smooth tube without any seam. This is attained by stitching the felt in a peculiar and novel manner as will be more fully explained farther on. The surface of the felt is provided with a layer of suitable fabric, preferably of silk which has been saturated with a rubber solution. When the surface of the roller has been somewhat impaired by continued use the roller is taken out of the machine, the silk surface removed and a new silk surface is applied easily and quickly.

The invention is illustrated in the accompanying drawing in which

Figure 1 is a perspective view of a platen or roller which embodies my invention. Fig. 2 is a plan view of a flat piece of felt showing a few parallel lace stitches not drawn together as yet. Fig. 3 is a plan view of part of said felt partly drawn together to illustrate the location of the stitches. Fig. 4 is a cross section through the platen, and Fig. 5 is a cross section on line 5, 5 of Fig. 2.

Similar characters of reference denote like parts in all the figures.

The platen or roller shown on the drawing is one newly manufactured according to this invention. It is however understood that both the felt and the silk tube surface may be applied to any existing roller of old construction. The silk cover alone also may be applied to any roller of old construction and even to the rollers made of hard rubber and the like when same show impressions on the surface from continued use.

In Fig. 1 *a* represents the bearing of the roller adapted to receive the shaft which car-

ries an iron front plate *b* of circular shape. A wooden cylinder *c* is supported by the bearing *a* in the usual manner, see Fig. 4. The felt is represented by the letter *d*. The silk cover is designated by the letter *s*, as shown in Figs. 1 and 4. The enumerated elements together with the shaft *e*, shown in section in Fig. 4, are all the elements of which the platen is composed.

The bearings, shaft, and wooden tube are assembled in the usual manner. The cylinder or tube of felt is made in the following manner: First a piece of felt of the desired thickness is cut into oblongs of the required size. An angular incision *f* is made near each end of the long sides of the felt as shown in Figs. 2 and 3. The purpose of this incision is to hide the stitches. In order to produce a smooth surface when the felt is formed into the tube or cylinder the stitching has to be done in a peculiar manner. The method of stitching which I prefer to call lace stitching is apparent from Figs. 2 and 3. A single thread is used. The needle is first inserted in the incision *f* and run out in the center line of the side *g* of the felt forming a stitch hole *h*. The thread is carried over to the other side *i* of the felt and the needle inserted directly opposite into the middle of the side and run out through the channel *f* forming a stitch hole *l*. Now the needle is inserted in the same incision *f* a little distance farther in and run again through the center of the side of the felt forming a stitch hole *l*. The thread is carried over to the long side *g* of the felt and the needle run through the center line and the channel *f* whereby the two threads are parallel to each other. The stitch hole *m* is thus formed. The needle is inserted somewhat farther in the incision *f* and forced through the center line of the side as above described and the thread again carried over to the other side whereby a continuous row of parallel stitches are produced. When the entire length of the felt has thus been stitched same is gradually drawn together as indicated in Fig. 3 and finally a cylinder or tube is formed. From this peculiar method of producing parallel lace stitches it is apparent that a tube is formed without showing any seam when finished and leaving an entirely smooth surface without any edge on the line of contact.

When thus prepared a piece of suitable fabric preferably of silk is saturated in a rubber solution and applied to the sur-

face of the felt. The rubber solution dries quickly and produces with the silk an excellent surface for the impact of the keys of the typewriting machine. The impact of the 5 keys on the felt cylinder with the silk surface saturated with rubber which also fills the pores does not produce any impressions on so pliable a surface and the roller lasts a long time. However as above stated if considered necessary the silk surface may be 10 peeled off and a new layer of silk put on in a short time and at a very small expense. Furthermore the weight of the novel platen has been greatly reduced and is about one 15 half of the platens of former constructions. This saves the wear and tear on the machine and the felt and silk also act as sound deadening materials.

Having thus described my invention I 20 claim as new and desire to secure by Letters Patent:

1. A platen or roller for typewriting machines comprising a wooden roller body with bearing and shaft, a tube or cylinder of felt 25 made in one piece and forming a tube by parallel laced stitches concealed within the material, and a layer of suitable fabric saturated in a rubber solution applied to the outer surface of the felt cylinder.
2. A platen or roller for typewriting machines comprising a wooden roller body with

bearing and shaft, a tube or cylinder of felt made in one piece and forming a tube by parallel laced stitches concealed within the material, and a layer of silk saturated in a rubber 35 solution applied to the outer surface of the felt cylinder.

3. The method of producing a platen or roller for typewriting machines consisting in preparing a felt cylinder by cutting the felt 40 into an oblong of the desired size, making an incision along the longitudinal sides and producing parallel lace stitches by inserting the needle in one incision, drawing it out in the center line of the one side, carrying the thread over, running it through the center line of the other long side and the second incision, passing the needle through the incision a little farther in and out in the middle of this long side and carrying the thread over, etc., 45 whereby parallel lace stitches result, drawing the lace stitches together until a tube or cylinder is formed, mounting the tube on the roller body, and applying a layer of silk saturated in rubber solution on the top surface of the felt cylinder.

Signed at New York, N. Y., this 9th day of July, 1906.

THOMAS F. NOLAN.
